E. J. MALLETT.

Tobacco Pipe Cartridge.

No. 38,052.

Patented March 31, 1863.

UNITED STATES PATENT OFFICE.

EDWARD J. MALLETT, OF NEW YORK, N. Y.

IMPROVEMENT IN PUTTING UP SMOKING-TOBACCO.

Specification forming part of Letters Patent No. **38,052**, dated March 31, 1863.

To all whom it may concern:

Be it known that I, EDWARD J. MALLETT, of the city, county, and State of New York, have invented a new and Improved Mode of Putting up Smoking-Tobacco; and I do hereby declare that the following is a full, clear, and exact description of the same, reference being had to the accompanying drawings, forming part of this specification.

This invention consists in what may be termed "tobacco-cartridges," or, in other words, in the manufacture of charges of tobacco of suitable quantity for filling a smoking-pipe in capsules of paper or other suitable material, with openings through or passing through them for draft and for causing the ignition of the charges at the center and the radiation of the fire in all directions therefrom, the objects thereby obtained being economy, convenience, and cleanliness.

Figure 1 in the drawings is a side view of one of my tobacco-cartridges. Fig. 2 is a central vertical section of my invention. Fig. 3 represents the piece of paper of which the capsule or cartridge case is made. Fig. 4 represents the paper folded and formed into a tube. Fig. 5 is a side view, partly in section, of the principal portion of the apparatus for making the cartridges. Fig. 6 is a side view of the same portion of the apparatus without the cup in which the cartridge is formed. Fig. 7 is a longitudinal central section of the plunger, which serves the purposes of giving the capsules or cases the proper form for the reception of the tobacco, of pressing the tobacco into them, and of finishing off the cartridges when closed.

A, Figs. 1 and 2, is the capsule or case of paper inclosing the charge *a* of tobacco, and combining therewith to make the cartridge, the form of which may be that of an inverted cone, as represented, or of a cylinder, according to the shape of the pipe in which it is to be used.

b is the central hole extending right through the cartridge and tapering upward. The lower portion of this hole *b* is widened in the form of an inverted funnel, to make the cavity *c* for the reception of the wad *d*, of loose raw cotton, which is to absorb the essential oil or other liquid matter eliminated from the tobacco in smoking.

B, Figs. 5 and 6, is a base of wood or other

material, having secured in it in an upright position a sharp-pointed taper pin, *e*, at the bottom of which, and concentric with it, is a cylindrical boss, *f*, the pin projecting above the said boss to a length about equal to or greater than the depth of the cartridges to be made.

C, Fig. 5, is a cup of wood or metal, the form of whose interior corresponds with the intended form of the exterior of the cartridge, preferably that of an inverted frustum of a cone. The bottom of this cup is of suitable conical or substantially similar convex form to produce the cavity *c* in the bottom of the cartridge, and in the center of it is an opening of suitable size to fit the pin *e* when the cup rests on the top of the boss *f*, and below this bottom there is formed a socket, *g*, to fit to the exterior of the boss *f*, upon which it is placed, to hold the cup in position for the filling and finishing of the cartridge.

The plunger E, Fig. 7, made of wood or other material, has one end, *n n*, made of a form to fit exactly to the sides and bottom of the cup C, and is bored centrally, as shown at *h*, for the reception of the pin *e*. The other end, *p*, of the said plunger is formed to fit in the mouth of the cup, and has a central hole, *i*, for the reception of the pin *e*, and is also slightly countersunk in such a manner as to produce a sharp edge, *j*, all round.

To make the capsules A, pieces of paper are cut of the form shown in Fig. 3, or of a form substantially the same, and each, after having paste, gum, or other suitable adhesive material applied along one edge, as indicated in red tint in Fig. 3, is folded over a suitable flat former in the lines *k k* and *l l*, the part outside of the lines *l l* forming a lap, *m*, as shown, and adhering to the part on which it laps. When the lap is dry, the paper, now in the form of a tube or bottomless bag, is placed on the lower portion, *n n*, of the plunger F, which fits the cup C, and pushed tightly over it, and its lower edges are turned into the wide mouth of the hole *h*. The plunger, with the paper upon it, is then placed in the cup C, which is placed over the pin *e* and boss *f*, as shown in Fig. 5, and the plunger drawn out, leaving the paper in the cup, as shown in red outline in that figure. The proper quantity of cut or granulated tobacco is then poured into the paper around the pin *e*, and rammed down with the end *p* of the plunger. The up-

per edges of the paper are then folded over and pressed down by reapplying the end *p* of the plunger with a suitable pressure. I generally propose, after folding over the upper edges of the paper, to cover them with a small circular piece of paper having its lower surface covered with adhesive material, which by the last application of the plunger is made to secure the said edges; but this may not be absolutely necessary. The capsule being closed up, the cartridge is complete, the central hole, *b*, having been formed by the pin *e*, and the cavity *c* by the convex or conical bottom of the cup. To remove the cartridge from the cup, the cup is removed from the boss *f* and pushed down upon the point of a blunt pin, *t*, which enters the hole in the bottom of the cup and pushes out the cartridge. The wad of cotton *d* may then be inserted or not, as may be desired; but I prefer always to use the wad.

To use the cartridge, it is placed in the pipe, which should be preferably so formed as to leave a space between its bottom and the bottom of the cartridge, and on the pipe being placed in the mouth the smoker applies fire to the hole *b*, while he draws in his breath, and the tobacco having been ignited at the center, the fire spreads quickly outward and ignites the whole upper surface of the charge. In smoking it burns regularly gradually downward until every particle has been consumed without waste, and the essential oil or liquid matter containing nicotine eliminated in the process is collected in the wad when the latter

is used. The pipe is then inverted and shaken, and the bottom of the capsule and the wad drop out, leaving the pipe clean.

One advantage of this invention consists in its utilizing much of the stock which is generally wasted in the tobacco manufacture, being too fine or small to be made into cigars or smoked loosely in a pipe. Another advantage consists in the convenience it affords for filling the pipe. Another is that there is none wasted in filling or by being left unconsumed at the bottom of the pipe. Another is that an easy and regular draft is insured; and with the use of the wad *d* the liquid matters eliminated are prevented from either collecting in and fouling the pipe-stem or from entering the mouth and producing unpleasant and deleterious effects.

I will remark that, instead of the cartridge being perforated all through, it may be perforated partly through from the bottom and partly from the top, the two perforations not quite meeting in the center of the cartridge.

What I claim as my invention, and desire to secure by Letters Patent, is—

A tobacco-cartridge consisting of a charge of tobacco of proper quantity for a pipe, put up in a paper capsule, and perforated centrally either entirely or partly through, substantially as herein specified.

E. J. MALLETT.
